BINOCULAR MICROSCOPE

John R. Miles, Glenview, Ill., assignor to Skil-Craft Corporation, Chicago, Ill., a corporation of Illinois

Application April 4, 1958, Serial No. 50,334

Term of patent 14 years

(Cl. D57—1)

Fig. 1 is a perspective view of a binocular microscope showing my new design;

Fig. 2 is a side elevational view thereof;

Fig. 3 is a front elevational view thereof; and

Fig. 4 is a cross-sectional view thereof taken on the line 4—4 of Fig. 2 on an enlarged scale, with parts broken away for convenience of illustration.

I claim:

The ornamental design for a binocular microscope, as shown and described.
